AIR AND EROSION OR CORROSION
ELIMINATOR DEVICEWilliam M. Kennedy, Lyndhurst, and Bengt E.
Meurk, Upper Montclair, N. J.

Application March 22, 1950, Serial No. 151,172

2 Claims. (Cl. 183—2.5)

1

This invention relates to devices for use in fluid circulating lines for the purpose of eliminating air from the fluid circulated therethrough and thus to retard or check formation of erosion or corrosion throughout the lines and the various pipes, fittings, valves, pumps and condensers. More particularly, the invention deals with a device of the character described employing a plurality of filter plates or screens to break-up the fluid flow or create a turbulence to free the air for discharge from the device and to accomplish this result without retarding flow of the circulated fluid. Still more particularly, the invention deals with the use of filter plates or screens composed of such materials as will encourage the formation of corrosion and be anodic to the various pipes, fittings and the like of the structure.

The novel features of the invention will be best understood from the following description, when taken together with the accompanying drawing, in which, certain embodiments of the invention are disclosed and, in which, the separate parts are designated by suitable reference characters in each of the views and, in which:

Fig. 1 is a side and sectional view of a device made according to our invention.

Fig. 2 is a section substantially on the line 2—2 of Fig. 1.

Fig. 3 is a sectional view of part of a modified form of screen which we employ; and

Fig. 4 is a face view of another form of screen. While our improved device is adapted for use in conjunction with circulation of fluids of any type or kind regardless of the location of the circulating apparatus, our invention has a distinct use on-board ship, particularly in the circulation of sea water and, from this standpoint, it is desirable that at least one of these devices be employed closely adjacent the intake of the circulating system, so as to free the air from the sea water before the same has an opportunity to reach the remainder of the system or the various devices or apparatus through which the water is circulated. It will be understood, however, that two or more of these devices can be employed along the circulating line, so as to render the system substantially fool-proof from the standpoint of dispensing with all air in the line.

In illustrating one adaptation of our invention, we have shown in Fig. 1 of the drawing, a cross-section through an eliminator which comprises a substantially T-shaped tubular body 10, having a flanged intake end 11 and a flanged discharge end 12, the body 10 having an upwardly extending central tubular portion 13 which is

substantially square in cross-sectional form, as will appear from a consideration of Fig. 2 of the drawing. The tubular portion 13 terminates at its upper end in an outwardly extending coupling flange 14 facilitating attachment of a domed portion or cap 15, also flanged, as seen at 16. Between the flanges 14 and 16 is disposed a perforated plate or screen 17, the parts being held together by a plurality of bolts 18.

Opposed side walls 19 of the body 13 and that portion of the walls extending into the cross-head portion of the device, in other words, the portions 20 have spaced vertical grooves 21. The grooves 21 are adapted to receive baffle screens or filter plates 22 having suitable apertures or openings 23 therein. The grooves 21 open outwardly through the upper flanged end 14 of the tubular portion 13 so that, in detaching the dome or cap 15, the plates 22 can be removed from time to time for cleaning and other purposes. With this thought in mind, it will be noted that the air vent pipe 24 which is coupled with the upper central portion of the dome or cap 15 has, at a predetermined position, above the body 10, a coupling 25 which will facilitate removal of the dome or cap 15 without disturbing the body 10 or the upper portion 24' of the vent pipe. The upper discharge end of the vent pipe has a downwardly bent fitting 26 for the discharge of air. It will be understood that the discharge 26 is disposed in widely spaced relationship to the body 10, particularly in uses on-board ship.

In Fig. 3 of the drawing, we have shown at 27 a modified form of screen plate which is corrugated, as seen at 28, these corrugations being disposed between boundary edge portions of the screen and it is preferred that the apertures or openings 29 be arranged at the high-points of the corrugations. The purpose of this construction is to further facilitate the freeing of the air to allow the same to pass upwardly through the tubular portion 13, the screen 17 or the apertures 17' therein and, thus, into the dome or cap 15 and out through the vent.

In Fig. 4 of the drawing, we have shown at 29 another form of screen in the form of a stamped sheet, providing a staggered arrangement of diamond-shaped openings 30 therein.

It will be understood that, by extending the tubular portion 13 a material degree above the flanged intake and discharge ends 11 and 12, a relatively large circulating chamber is provided which is materially greater than the bore of the circulating passage through the device such, for example, as the bore 11', so that the various baf-

file screen plates employed will not retard the flow of fluid through the system. In other words, the area of the openings in the baffle screen plates will be greater than the area of the bore 11. In addition to breaking-up the fluid to free the air for discharge through the vent, the baffles will also prevent circulation of any large foreign matter through the system and erosion which takes place will take place upon the baffle screen plates and, as pointed out above, these can be cleaned from time to time or replaced by new plates without materially holding-up the system.

The last plate or screen, namely the plate or screen 22' of a series is preferably made heavier to form a support or backing to check passage of broken-down portions or sections of other plates or screens through the system. This breakdown would occur in the event that the device had not been checked for a long period of time. It is recommended, however, that periodic checkings be made for replacement or removal of the plates.

It will also be understood that the vent pipes 24 can be used as a discharge or bleeder pipe for discharge of a small quantity of the aerated water or, in other words, to encourage such discharge to avoid checking escape of air. In some installations of the device, the same will be disposed below the water line of the ship and, thus, a water level will be maintained in the pile 24, but the discharge will be carried to a point above the water line.

It will be apparent that, by utilizing filter or screen plates of ferrous metals or metals in the anodic group, erosion or corrosion has a concentrated effect upon these plates, thus minimizing or eliminating the possible formation throughout the various pipes, fittings and the like of the structure. By positioning several of the devices in question throughout a system, a substantially positive control can be provided which will result in long life use of the various pipes, fittings and the like of a system and the only loss effected is the loss in replacement of the filter plates or screens having the corrosion concentrated thereon. In other words, where the structure includes pipes, fittings and the like which are composed of brass or copper, by utilizing screen plates composed of iron, these plates would constitute the weak members and be more readily attacked by the free oxygen in the water.

Having fully described our invention, what we claim as new and desire to secure by Letters Patent is:

1. An air and erosion eliminator device for circulating systems through which aerated water is circulated, said device comprising a T-shaped tubular body having opposed flanged inlet and outlet ends, an intermediate portion including an upwardly extending air outlet portion substantially

rectangular in cross-sectional form, the intermediate portion forming a straight line communication between said inlet and outlet ends, a domed cap for said air outlet portion, a horizontal screen arranged and secured between the cap and air outlet portion, a plurality of screens arranged vertically in said device and extending into said air outlet portion and abutting said horizontal screen, said screens forming baffles for liberating air intermediate the intake and discharge ends of the device for discharge into said outlet portion, a vent pipe coupled with and communicating with said domed cap, and the screens of said device comprising perforated iron plates having anodic characteristics encouraging formation of corrosion thereon.

2. An air and erosion eliminator device for circulating systems through which aerated water is circulated, said device comprising a T-shaped tubular body having opposed flanged inlet and outlet ends, an intermediate portion including an upwardly extending air outlet portion substantially rectangular in cross-sectional form, the intermediate portion forming a straight line communication between said inlet and outlet ends, a domed cap for said air outlet portion, a horizontal screen arranged and secured between the cap and air outlet portion, a plurality of screens arranged vertically in said device and extending into said air outlet portion and abutting said horizontal screen, said screens forming baffles for liberating air intermediate the intake and discharge ends of the device for discharge into said outlet portion, a vent pipe coupled with and communicating with said domed cap, and the screens of said device comprising perforated iron plates having anodic characteristics encouraging formation of corrosion thereon, and the plate at the outlet end of the device being thicker than the other plates.
